MACHINE FOR WINDING BOBBINS

Brooks Marcellus, Rockford, Ill., assignor to
Barber-Colman Company, Rockford, Ill., a corporation of Illinois

Application March 23, 1944, Serial No. 527,702

18 Claims. (Cl. 242—32)

1

The invention pertains to yarn winding machines, and more especially to machines for producing filling wound bobbins, sometimes known as cops or pirns.

The primary object of the invention is to provide a substantially trouble-free driving and control mechanism for such machines.

More specifically stated, the invention aims to provide a mechanical control mechanism eliminating difficulties heretofore experienced with electrical controls commonly embodied in machines of this character.

For another object, the invention provides a conveniently adjustable drive mechanism for the feed of the yarn traversing means.

The objects of the invention thus generally stated, together with other and ancillary advantages, are attained by the construction and arrangement shown by way of illustration in the accompanying drawings forming a part hereof, in which:

Figure 1 is a fragmentary front elevational view of one end of a winding machine having a portion of the housing enclosing the improved driving and control mechanism, broken away and shown in section.

Fig. 2 is a transverse sectional view looking from the right in Fig. 1.

Fig. 3 is a fragmentary perspective view of said mechanism.

Fig. 4 is a fragmentary front elevational view showing the control mechanism and the relation of the parts at the beginning of the control cycle.

Fig. 5 is a fragmentary vertical sectional view looking in a direction opposite from that of Fig. 2 and taken approximately in the plane of line 5—5 of Fig. 1.

The present invention constitutes an improvement upon the bobbin winding machine disclosed in my copending application, Serial No. 450,129, filed July 8, 1942, now Patent No. 2,409,639, dated October 22, 1946, and in particular upon the driving and control mechanism for such machine, the present application being subordinate to said application Serial No. 450,129. The mechanism comprises means for driving the winding spindles as well as the yarn traversing means therefor, and control means operative upon the completion of one winding cycle to condition the parts for the next winding cycle.

Referring now to Fig. 1 of the drawings, I have shown the improved driving and control mechanism arranged at the left end of a winding machine of the general character set forth in said

2

copending application. The winding and traverse mechanism forms part so no part of the present invention, so that a full disclosure thereof is deemed unnecessary. In brief, it comprises a series of winding units (one only being herein shown) each including a spindle 10 (Fig. 2) between which and a centering slide 11 is supported the bobbin 6 which is to be wound. 12 designates an empty bobbin hopper equipped with suitable means 13 (Fig. 1) for delivering bobbins one at a time into position for engagement between the centering slide 11 and a chuck 14. The strand to be wound extends from a suitably supported yarn mass 15 through a tensioning device 16 and then over a guide 17 to the bobbin, being initially gripped between the butt end of the bobbin and the chuck 14 in the well known manner.

The spindles are driven from a main drive shaft 18 extending longitudinally through the machine. 20 Each spindle is connected to the shaft 18 by means of bevel gears 19 and 20, a horizontal stub shaft 21 and spur gears 22 and 23, the gear 23 being fast upon a rearward extension of the spindle.

25 The yarn traversing means comprises, as in the case of the machine of said copending application, a hollow cylindrical member or cam sleeve 24 encircling each winding spindle and unidirectionally rotated. The sleeve has helical cam surfaces 25 at its forward end for imparting a traversing movement to the running strand. The sleeve is advanced progressively axially of the bobbin to produce a filling wound bobbin. For supporting the sleeve each unit comprises a slide 26 suitably supported in ways 27 (Fig. 1) upon the machine frame. The traverse slide is thus mounted for horizontal movement forwardly relative to the spindles during the winding operation and rearwardly preliminary to the succeeding winding operation.

35 Continuous rotational movement is imparted to each traversing cam during each winding operation. As herein shown, the drive is from a shaft 28 parallel to and connected with the main drive shaft by suitable spur gearing 29 (Fig. 1). From the shaft 28 the driving connection extends through a vertical stub shaft 30 (Fig. 2) and two sets of bevel gears 31 and 32, one of the latter set being splined upon a shaft 33 extending parallel to the axis of the spindle and connected to the traverse sleeve by spur gearing 34 enclosed in a gear housing 35 on the slide 26.

For imparting axial feed movement to the traverse slide 26 relative to the winding spindles, 55 the drive mechanism includes a traverse drive

shaft 36, herein extending longitudinally of the machine above and rearwardly of the main drive shaft 18. On said shaft 36 are pinions 37 (one only being shown) each meshing with a rack 38 rigid with one of the slides.

The improved drive mechanism is compactly arranged within a housing 39 which, as above indicated, is located at one end of the machine. The main and traverse drive shafts extend into and are suitably journaled in this housing. Power is supplied by an electric motor 40 mounted upon the housing. For this purpose, the motor has a belt and pulley driving connection 41 with a shaft 41^a axially aligned with the main drive shaft 18 and having a clutch controlled connection therewith. Preferably, a combined clutch and brake unit of well known construction is employed for this purpose, said unit embodying a clutch 43 and a brake 44.

The traverse drive shaft 36 has a disengageable driving connection with the main drive shaft, comprising a feed shaft 42 (Fig. 3) extending in the present instance in a front to rear direction and having a worm 45^a at its rear end meshing with the worm wheel 45 fast on the traverse drive shaft 36. At its forward end the feed shaft 42 is connected by bevel gearing 46 with a longitudinal shaft 47 arranged to be driven from the main drive shaft 18 in a manner presently to appear. The feed shaft 42 is mounted upon an elongated bracket 48 pivoted to turn on the axis of the shaft 47 so as to permit disengagement of the worm 45^a from the worm wheel 45 by cam means forming a part of the control mechanism as hereinafter set forth.

The operative connection between the main drive shaft 18 and the feed shaft 42 comprises in general a roller ratchet mechanism. This is of advantageous character, capable of easy adjustment to vary the rate of advance of the traversing cams relative to the bobbins being wound to meet varying conditions in use, as when changing from one size of yarn to the other.

In the preferred embodiment, the roller ratchet actuator comprises (Figs. 3 and 5) a disk 49 fast on the shaft 47 and a roller 50 having end trunnions loosely supported in the notched arms 51 of a U-shaped rocker member 52 loose on the shaft 47. A driving plate 53 forming part of a downwardly opening housing 54 provides an inclined or wedge surface for coaction with the roller 50 and disk 49 upon oscillation of the housing, the roller being wedged between the driving plate and the disk as the plate is rocked in one direction (to the right in Fig. 5) so as to impart an advancing movement to the feed shaft 47.

For actuating the housing 54, I provide a pitman 55 having an eccentric connection 55^a with a shaft 56 geared to the main drive shaft 18 by spur gears 58 and 59. While the length of stroke imparted to the housing by its eccentric drive is constant, the extent of movement imparted to the feed shaft is made variable. To this end, the rocker member 52 has a stop lug 60 urged by a spring 61 toward an adjustable stop member 61^a. The latter serves to limit the return movement of the roller 50 in the oscillation thereof, thereby varying its position relative to the plate 53 and determining the increment of movement imparted to the disk 49 and thereby to the shaft 47.

To facilitate easy adjustment of the stop member 61^a, the latter has formed integral therewith an arcuate gear segment 62 meshing with a pinion 63 fast on the rockshaft 64. The latter extends through the housing at the side adjacent

the machine frame as shown in Fig. 1 and the projecting end has fast thereon a segment 65 (Fig. 3) equipped with a convenient handle 66 and having teeth 67 for engagement by a spring-pressed detent 68.

As in the case of the control mechanism disclosed in my copending application Serial No. 450,129, the clutch and brake unit 43, 44 controlling the drive for the winding spindles, the advance of the slide carrying the traverse cams, and the rotation of the latter is actuated mechanically. An important feature of the present invention resides in the actuation mechanically instead of electrically of a second clutch and brake unit governing the operation of cam means for controlling or conditioning various operating mechanisms of the machine. This second clutch and brake unit comprises a clutch 69 and brake 70, and provides a connection between a driving shaft 71 and an axially aligned shaft 72 connected by a two step reducing gear train composed of a pinion 73, spur gear 74, pinion 75 and spur gear 76, the latter fixed upon a shaft 77.

The shaft 77 carries various cams (not all of which are herein shown) for the control of various mechanisms, substantially as set forth in said copending application, and, in addition thereto, various cams, as will appear, for the control of the two clutch and brake units. The driving shaft 71 of the second clutch and brake unit has a belt and pulley driving connection 78 (Fig. 1) with the driving shaft 41^a of the main clutch and brake unit.

For operating the clutch 43 of the main clutch and brake unit 43, 44, a shifter lever 79 (Fig. 3) is provided. This lever is mounted upon a rock-shaft 80 and has one end, herein the upper end, operatively associated with a clutch shifting collar 81. Another, or depending arm, 82 carries a roller 83 for coaction with an arcuate cam 84 on the cam disk 85 fast on the cam shaft 77. A third arm 86 is connected by a spring 87 to an adjustable anchoring screw 88, said spring being placed under tension in the clutch engaging movement of the collar by said cam 84. The clutch is held engaged by a latch device comprising an arm 89 fast on the rockshaft 80 and a latch member 90. The latter is mounted loosely on the rear end of a control shaft 91 and is urged by a spring 92 into operative relation to the arm 89.

The control shaft 91 extending, in the present instance, in a front to rear direction, is suitably supported in the housing. It is arranged for actuation in response to the movement of the traverse cam slide for the purpose of actuating the clutch and brake unit 69, 70 to initiate operation of the cam shaft upon the completion of one winding cycle. For this purpose, the control mechanism includes a control member, herein in the form of a vertically movable rack bar 93 connected with the traverse drive shaft 36 by means of a pinion 94. A part on the rack bar, such as an adjustable stud 95, is arranged in operative relation to a roller carrying arm 96 fast on the control shaft. An arm 97 rigid with the arm 96 is engageable with an arm 98 rigid with the latch 90. The two arms 97 and 98 thus provide a lost motion connection between the vertically movable control bar 93 and the latch member 90, providing a timed delay near the end of the winding operation following which the latch member is actuated to effect a disengagement of the clutch 43 and the application of the brake 44 to stop the rotation of the winding spindles 75 and the advance of the traverse cam slide 26.

The timed delay interposed by the lost motion aforesaid is utilized for the conditioning of two springs 99 and 100, respectively, associated with the opposite ends of a shifting lever 101 for the clutch and brake unit 69, 70 of the cam shaft drive. As shown, the clutch lever 101 is pivoted between its ends. The spring 99 is connected at one end to the upper end of the lever, and at its other end to one arm 102 of a bell crank 103 fast on the forward end of the control shaft 91. To the opposite or lower end of the lever 101 is connected the spring 100 which, in turn, connects with one end of a rocker arm 104 loose on a shaft 105. The free end of the rocker arm 104 is adapted for engagement by a latch 106 operatively connected with the control shaft by means of a link 107, the latter having its upper end connected to an arm 108 of the bell crank 103. Its other end has a pin and slot connection 109 with the latch member 106.

Near the end of the winding operation the control stud 95 engages the roller arm 96 and rocks the control shaft clockwise, turning the bell crank 103 on the forward end of the shaft so that the spring 99 is placed under tension. At this time, the clutch lever 101 is restrained from movement by a latch member 110 engaging with a block 111 on the lower end of the clutch lever.

At the end of such spring tensioning operation and in the continued rocking movement of the control shaft, the latch 106 is disengaged from the rocker arm 104 by the connection of the link 107 acting through the pin and slot connection 109. This releases the rocker arm 104 to movement so as to permit unloading of the spring 100 which is connected with the lower end of the clutch lever, thereby conditioning the latter for operation by the spring 99 which at this time is held under tension by the latch 110. By the time the winding operation has been completed, the control shaft 91 will have turned far enough to take up the lost motion between the arms 97 and 98 at the rear end of the shaft, so that the latch member 90 is then disengaged from the arm 89 so as to permit disengagement of the main clutch 43 and application of the brake 44 by the spring 87.

Notwithstanding the disengagement of the clutch 43 and the application of the brake 44, the traverse cam slide 26 continues to advance for a short distance by the action of momentum, and such coasting of the slide is utilized to trip the latch 110 so as to initiate the operation of the cam shaft. For this purpose, a third arm of the bell crank 103 has a pin-and-slot connection 113 with a link 114 connected to an arm 110 of the latch member 110. The pin and slot connection 113 is of such length as to permit a clockwise turning movement of the control shaft 91 far enough before disengagement of the main clutch to tension the spring 99 and unload the spring 100. When the latch 110 is finally tripped, the spring 99 actuates the clutch lever 101, thereby disengaging the brake 70 and engaging the clutch 69 so as to start the cam shaft through an operating cycle.

During the cam shaft cycle the clutch is held engaged by another latch 115, also operatively associated with the clutch lever 101. This latch 115 engages with the latch block 111, on the side thereof opposite the latch 110. The two latches are mounted on suitably fixed pivots and have depending arms connected by a contractile spring 116 so arranged as to tend to swing both latches

into active position relative to the latch block 111. Movement of the lever 101 in opposite directions is limited by opposed stops 101a.

As soon as the cam shaft has been started, the cam disk 117 operates to disengage the driving connection between the feed shaft 42 of the traverse cam mechanism and the traverse drive shaft 36. For this purpose, the bracket 48 has a roller follower 118 engaging with the periphery of the cam disk 117, the cam being operative to disengage the drive by lifting the worm 45a out of mesh with the worm wheel 45.

Upon disengagement of the feed for the traverse slide, the latter is returned to its initial or retracted position. For this purpose, a lever 119 (Fig. 5) has a gear segment 120 meshing with the lower end of the control rack 93. The lever is actuated by the cam disk 117 to lower the rack bar, and through the gearing connection between the bar and the traverse drive shaft 36, causes the slide to be returned.

The lever 119 is pivoted at 121 and carries a roller follower 122 for coaction with a cam groove 123 in one face of the cam disk 117. In Fig. 5 the lever is shown in the position occupied during the winding operation with the cam shaft stationary. As the winding operation progresses, the lever, being connected with the traverse drive shaft 36 through the vertical control bar 93, moves upwardly relative to the cam disk. The cam groove is suitably recessed at 124 for receiving the roller in such vertical movement of the control bar, and the recess is shaped to form a cam surface 125 operative after disengagement of the feed to swing the lever downwardly and impart a counterclockwise rotation to the traverse drive shaft 36, resulting in the return of the traverse cam slide 26. As the rack bar 93 moves downwardly in such return of the traverse slide, the control stud 95 thereon moves away from the roller arm 96, thereby permitting the control shaft to move in a counterclockwise direction (Fig. 3). This relieves the tension of the spring 99 and allows latches 90 and 106 to enter relative to their respective latch arms 89 and 104.

At the beginning of the cam shaft cycle the actuating spring 100 for the lower end of the clutch lever is energized preparatory to the disengagement of the clutch 69 and the application 50 of the brake 70 to stop the cam shaft. For this purpose, a rib cam 126 secured on the cam disk 117 engages with a roller 127 on an arm 128, the latter being connected by an elongated member 129 with the rocker arm 104. The cam rocks the arm 128 and thereby the rocker member 104 clockwise (Fig. 3) and, in so doing, tensions the spring 100, the latch 106 finally entering into position relative to the upper end of the arm 104.

Near the end of the cam shaft cycle, another arcuate cam rib 130 on the cam disk 117 engages with a roller follower 131 on a second rocker arm, this arm being connected by an elongated member 133 to a depending arm 134 which is connected by a link 135 with the latch 115. When the cam 130 engages the roller 131, the arm is swung in a direction to withdraw the latch 115 from engagement with the block 111 with the result that the lever 101 is actuated by the spring 100 to disengage the clutch and apply the brake.

The cam shaft may be brought to rest manually at any time during its cycle. To this end, a latch operated lever 136 is pivoted adjacent the latch 115 for coaction with an arm 137 thereon. The other end of the lever 136 is connected by a link 138 arranged for operation by a hand lever 139

(Fig. 1) normally held in inoperative position relative to the latch 137 by means of a spring 140. The latter is interposed between a collar 141 on the rod and one wall of the main housing, movement of the rod by the spring being limited by another collar 142.

The hand lever 139 is fast on the forward end of a rockshaft 143 which extends rearwardly in the housing and carries on its rear end an arm 144 connected by a link 145 to the latch disengaging rocker member 98. The link 145 has a pin and slot connection 146 with the rocker member 98 and the arrangement is such that when the hand lever is swung to the right (Fig. 1) the cam shaft will be tripped by lever 136 without disengaging the clutch for the main drive. When, however, the hand lever is swung to the left, the rocker member 98 is swung in a direction to disengage the latch 90, thereby releasing the clutch lever 79 to the action of the spring 87 and stopping the main drive.

Summary of operation.—When the bobbin is being wound, the cam shaft is idle, its clutch 69 being disengaged; and the main drive shaft 18 is in operation, the clutch 43 being held engaged by the latch 90. Consequently the feed shaft 42 is being driven by the roller ratchet drive mechanism, causing the traverse drive shaft to actuate the traverse cam slide through the connection formed by the pinion 37 and rack 38 (Fig. 2). At the same time, each traverse cam is driven unidirectionally through its connection with the main drive shaft including the two sets of bevel gears 31 and 32. If it is desired to adjust the rate of feed as, for example, in changing from one yarn size to the other, the active stroke of the roller ratchet mechanism is adjusted by releasing the detent 68 and manually adjusting the position of the roller engaging plate 53.

As the end of the winding operation approaches, the control stud 95 on the rack bar 93 moves into engagement with the roller arm 96 turning the control shaft in a clockwise direction preparatory to the actuation of the cam shaft clutch to start the cam shaft cycle. In the initial portion of this turning movement of the control shaft, the spring 99 is placed under tension, the latch 110 having moved into blocking position relative to the end of the clutch lever 101 upon termination of the previous cam shaft cycle. Also the latch 106 is moved upwardly out of engagement with the rocker 104 to relieve the tension of the spring 100. Thereupon, the latch 90 is withdrawn by the arm 97 on the rear end of the control shaft picking up the arm 98, thereby permitting the spring 87 to disengage the clutch 43 and engage the brake 44. Upon the disengagement of the clutch 43, momentum carries the traverse cam forwardly far enough to take up the pin-and-slot connection 113 between the forward end of the control shaft and the latch 110. Operation of this latch releases the clutch lever to the action of the spring 99 to cause the cam shaft clutch 69 to be engaged and it is held engaged by latch 115.

At the beginning of the cam shaft cycle, the driving connection between the feed shaft and the traverse drive shaft is disengaged by operation of the disk cam 117 acting upon the swinging bracket 48. Thereupon the lever 119 (Fig. 5) is actuated by the cam surface 125 to move the control bar downwardly and through its connection with the traverse slide to move the latter rearwardly to its initial position. The downward movement of the rack causes the control stud 95

on the rack bar 93 to move away from the roller arm 96 and thus permit the control shaft to turn counterclockwise, relieving the tension on the control shaft spring 99. Immediately after the cam shaft has started, the rib cam 126 rocks the member 104 to place the spring 100 under tension, the latch 106 having been lowered in the counterclockwise movement of the control shaft so as to enter relative to the rocker 104 and hold the spring under tension.

Near the end of the cam shaft cycle, the arcuate rib cam 84 on cam disk 85 engages with roller 83 on the lower end of the main clutch shifting lever 79 to reengage this clutch for the start of a new winding cycle. Finally, rib cam 130 rocks member 133 to disengage latch 115, freeing the clutch lever 101 to the action of spring 100, thereby disengaging the clutch 69 and applying the brake 70 to stop the cam shaft.

When it is desired to stop the machine during a cam shaft cycle, hand lever 139 is shifted to the right to actuate link 138 and lever 136 connected therewith, so as to swing latch 115 out of blocking relation to the clutch lever 101, it being remembered that the spring 100 was previously tensioned at the beginning of the cam shaft cycle. To stop the machine during the winding operation, the hand lever 139 is shifted to the left to withdraw latch 90 through the operation of link 145 and rocker member 98, thereby disengaging the main clutch.

I claim as my invention:

1. A bobbin winding machine having, in combination, a yarn traversing device and drive means therefor operative to impart movement to the device axially of the bobbin being wound, a cam shaft having cam means operative in the rotation of the shaft to effect return movement of the traversing device, said shaft having drive means including a clutch of the friction disk type with a shifting member, a spring for actuating said shifting member, means operable in the movement of the traversing device to energize said spring, a latch restraining said clutch shifting member against actuation by said spring, and a controller operative mechanically in the movement of the traversing device at the end of the winding operation to disengage said latch and release the clutch to the action of said spring whereby to start the cam shaft.

2. A bobbin winding machine having, in combination, a yarn traversing device and drive means therefor operative to impart movement to the device axially of the bobbin being wound, a cam shaft having a clutch and cam means operative in the rotation of the shaft to effect return movement of the traversing device, a clutch actuating spring energized in the movement of said device, a latch restraining said clutch against actuation by said spring, and a control means operative mechanically at the end of the winding operation to disengage said latch and release the clutch to the action of said spring whereby to start the cam shaft, said control means comprising a member connected with said drive means for movement thereby, and a rock-shaft arranged for actuation by said member and operatively connected with said latch.

3. A bobbin winding machine having, in combination, a yarn traversing device and drive means therefor operative to impart an advancing movement to the device axially of the bobbin being wound, a cam shaft having a clutch, and cam means operative in the rotation of the shaft to effect return movement of the traversing de-

vice, a spring for actuating said clutch, a latch restraining said clutch against actuation by said spring, and a control device operative in the advancing movement of the traversing device by said driving means to energize said spring and disengage said latch, successively.

4. A bobbin winding machine having, in combination, a yarn traversing device and drive means therefor operative to impart movement to the device axially of the bobbin being wound, said drive means including a clutch, a cam shaft having a clutch and cam means operative in the rotation of the shaft to effect return movement of the traversing device, a spring for actuating the cam shaft clutch, a latch restraining said clutch against actuation by said spring, and a control device operative in the movement of the traversing device to energize said spring, actuate said drive clutch to stop the drive means, and disengage said latch for the cam shaft clutch, successively.

5. A bobbin winding machine having, in combination, a yarn traversing device, a movable support for said device, driving means for said support including a main clutch, and a control mechanism for said device comprising a cam shaft, a clutch controlling the application of power to the shaft, a control member operatively connected with said driving means for actuation thereby, means actuated by said control member in its movement to actuate said main clutch to interrupt the drive to said support, and means actuated mechanically in the coasting of said support following the interruption of said drive to actuate the cam shaft clutch whereby to start the cam shaft.

6. A bobbin winding machine having, in combination, a yarn traversing device and driving means therefor operative to impart forward movement to the device axially of the bobbin being wound, and a control mechanism operative upon the completion of a winding operation to return said device, said mechanism comprising a cam shaft and a control element therefor, a spring for actuating said control element to stop the cam shaft, means actuated mechanically by the cam shaft in the return movement of the traversing device to tension said spring, and a latch device releasably holding said spring under tension.

7. A bobbin winding machine having, in combination, a yarn traversing device and driving means therefor operative to impart forward movement to the device axially of the bobbin being wound, and a control mechanism operative upon the completion of a winding operation to return said device, said mechanism comprising a cam shaft, a clutch controlling the application of power to the shaft, spring means for actuating said clutch in opposite directions to start and stop said cam shaft, a pair of latch devices operative to hold the clutch against movement in opposite directions respectively, means actuated as an incident to the approach of the traversing device to the forward end of the bobbin being wound to disengage one of said latch devices to cause the cam shaft to be started, and means actuated by the cam shaft near the end of a predetermined operating cycle to actuate the other one of said latch devices whereby to effect stoppage of the cam shaft.

8. A bobbin winding machine having, in combination, a yarn traversing device and driving means therefor operative to impart forward movement to the device axially of the bobbin

being wound, and a control mechanism operative upon the completion of a winding operation to return said device, said mechanism comprising a cam shaft, a clutch controlling the application of power to the shaft, spring means for actuating said clutch in opposite directions to start and stop said cam shaft, means operative in the approach of the traversing device to the forward end of the bobbin being wound to render said spring means effective to start the cam shaft, and means actuated by the cam shaft near the end of a predetermined operating cycle to render the spring means effective to stop the cam shaft.

9. A bobbin winding machine having, in combination, a yarn traversing device and driving means therefor operative to impart forward movement to the device axially of the bobbin being wound, and a control mechanism operative upon the completion of a winding operation to return said device, said mechanism comprising a cam shaft, a clutch controlling the application of power to the shaft, spring means for actuating said clutch in a direction to stop said shaft, means operative in the rotation of said shaft to energize said spring, latch means for maintaining said spring energized, a second latch means restraining movement of the clutch by said spring, and means operative near the end of a predetermined cycle of the cam shaft to disengage said second latch means.

10. In a bobbin winding machine, the combination of a yarn traversing device and drive means therefor operative to move the device axially of the bobbin being wound, and a control mechanism acting upon the completion of one winding operation to condition the machine for the succeeding operation, said mechanism comprising a cam shaft, a clutch controlling the application of power to the shaft, a lever for operating said clutch, a pair of springs operative upon said lever to move it in opposite directions, a pair of latch devices respectively operative to hold said lever in either clutch-engaged or clutch-disengaged position, and means actuated in timed relation to the movement of said traversing device and operative to tension the clutch-engaging spring, to unload the clutch-disengaging spring, and to disengage one of said latch devices.

11. In a bobbin winding machine, the combination of a winding spindle and drive means therefor, a member connected with said drive means for movement thereby during the winding operation, and a control mechanism operative upon the completion of one winding operation to condition the machine for the succeeding winding operation, said mechanism comprising a cam shaft, a clutch controlling the application of power to the shaft, a lever for operating said clutch, a pair of springs operative upon said lever to move it in opposite directions, latch means for holding said lever either in clutch-engaged or clutch-disengaged position, and means actuated by said member to tension the clutch-engaging spring, to unload the clutch-disengaging spring, and to operate said latch means whereby to effect engagement of said clutch.

12. In a bobbin winding machine, the combination of a yarn traversing device and drive means therefor operative to move the device axially of the bobbin being wound, a member connected to said drive means for movement in timed relation to said traversing device, and a control mechanism acting upon the completion of one winding operation to condition the machine for the succeeding winding operation, said

mechanism comprising a cam shaft, a clutch controlling the application of power to the shaft, a lever for operating said clutch, a pair of springs respectively operative upon said lever to move it in opposite directions, a pair of latch devices for holding said lever either in clutch-engaged or clutch-disengaged position, means actuated by said member to tension the clutch-engaging spring, to unload the clutch-disengaging spring and to disengage one of said latch devices, to start the cam shaft, and means operative in the rotation of the cam shaft to unload the clutch-engaging spring, tension the clutch-disengaging spring and disengage the other one of said latch devices, all in predetermined sequence.

13. A bobbin winding machine comprising, in combination, a yarn traversing device mounted for movement axially of a bobbin being wound, a main drive shaft, a feed mechanism for said device including a feed shaft, a roller ratchet driving connection between said drive shaft and said feed shaft comprising an actuating member reciprocable through a predetermined stroke in the rotation of the drive shaft, a disk operatively connected with the feed shaft, a rocker member having a roller for engagement with said disk in the movement of said actuating member in one direction, and stop means adjustable to shift the position of the roller to vary the point of engagement therewith by said actuating member.

14. A bobbin winding machine comprising, in combination, a yarn traversing device mounted for movement axially of a bobbin being wound, a main drive shaft, a feed mechanism for said traversing device including a traverse drive shaft, a feed shaft having an operative connection with said traverse drive shaft, a roller ratchet device for actuating said feed shaft, including a driven disk operatively connected with the feed shaft, an actuating member reciprocable by said drive shaft and a rocker member having a roller for movement into driving engagement with said disk in the reciprocation of said actuating member, adjustable stop means for determining the position of the roller relative to the actuating member whereby to vary the length of stroke imparted to the driven disk, and manually operable means for adjusting said stop means.

15. A bobbin winding machine having, in combination, a winding mechanism including a winding spindle and drive means therefor, and a control mechanism governing the operation of said winding mechanism including a cam shaft and drive means therefor, each of said drive means including a drive shaft, a driven shaft and a combined clutch and brake unit having an operating member shiftable in one direction to engage the clutch and in the other direction to disengage the clutch and engage the brake, and said control mechanism comprising two springs to actuate respectively the operating members of the two units, one of said springs tending to move the operating member of the spindle drive unit from clutching to braking position, and the other tending to move the operating member for the cam shaft drive unit from braking to clutching position, latches respectively restraining movement of said operating members by their respective springs, and means acting at a predetermined time in the operation of the winding mechanism to disengage said latches to effect stoppage of the spindle driving means and starting of said cam shaft.

16. A bobbin winding machine having, in combination, a winding mechanism including a wind-

ing spindle and drive means therefor, and a control mechanism governing the operation of said winding mechanism including a cam shaft and drive means therefor, each of said drive means including a drive shaft, a driven shaft and a combined clutch and brake unit having an operating member shiftable in one direction to engage the clutch and in the other direction to disengage the clutch and engage the work, and said control mechanism comprising two springs to actuate respectively the operating members of the two units, one of said springs tending to move the operating member of the spindle drive unit from clutching to braking position, and the other tending to move the operating member for the cam shaft drive unit from braking to clutching position, latches respectively restraining movement of said operating members by their respective springs, means acting at a predetermined time in the operation of the winding mechanism to disengage said latches to effect stoppage of the spindle driving means and starting of said cam shaft, a third spring for shifting the operating member of the cam shaft drive unit from clutching to braking position, means operative in the rotation of the cam shaft for tensioning said third spring, a third latch holding said member against movement from clutching to braking position, and means acting in the rotation of the cam shaft to disengage said third latch.

17. A bobbin winding machine having, in combination, a winding mechanism including a winding spindle, and a control mechanism governing the operation of the winding mechanism comprising a cam shaft and drive means therefor, said drive means including a clutch and brake unit and an operating member shiftable in one direction to engage the clutch and in the other direction to engage the brake, and said control mechanism comprising a lever for shifting the operating member, clutch engaging and disengaging springs respectively operable upon said lever to shift the member in opposite directions, means operable automatically upon completion of a winding operation to render said clutch engaging spring effective to start the cam shaft, and means operable in the rotation of the cam shaft to render the clutch disengaging spring effective to stop the cam shaft.

18. A bobbin winding machine having, in combination, a winding mechanism including a spindle and drive means therefor, a control mechanism governing the operation of said winding mechanism including a cam shaft and drive means therefor, each of said drive means including a drive shaft, a driven shaft and a combined clutch and brake unit with a shifter member and spring means for actuating the shifter member, and separate means successively rendered operative to actuate the two shifter members whereby to stop the winding mechanism and start the control mechanism.

BROOKS MARCELLIUS.
